UNITED STATES PATENT OFFICE.

CHARLES E. FISHER, OF BALTIMORE, MARYLAND, ASSIGNOR, BY MESNE ASSIGNMENTS, TO THE FISHER AUTOMATIC BRUSH MACHINE COMPANY, INC., OF BALTIMORE, MARYLAND, A CORPORATION OF MARYLAND.

BRUSH-MAKING MACHINE.

Application filed January 11, 1923. Serial No. 612,034.

This invention relates to brush-making machines of the type wherein wisps of fiber or bristle are automatically gathered from a magazine and carried to stapling mechanism which applies staples to the wisps and secures them to the brush blocks in the form of tufts. Such a machine is illustrated in my co-pending application, Serial No. 479,253, filed June 21, 1921. The present invention relates more particularly to a tuft guide which co-operates with the tuft-applying devices to form and guide the tufts and to keep the previously applied tufts out of the path of the tuft-applying devices. As heretofore constructed, these tuft guides have been given a forward swinging or linear movement to clear the applied tufts out of the way of the reciprocating stapling devices and to position the guide to receive said devices, and a backward movement to carry the tuft guide to the rear of the applied tufts so that it may press these tufts out of the way before the next descent of the stapling devices. A guide constructed and operating in this way is shown in the machine illustrated in the above identified application, and also in various patents granted to others as, for instance, the patent to Lebherz, No. 920,588, and the patent to Young & Lebherz, No. 982,340. Where the tufts are long, this requires a relatively long swinging or reciprocating movement of the tuft guide in order that the guide may, in its backward movement, swing over and entirely to the rear of the applied tuft. The tuft guide of my invention is so constructed that it may be given a rotary movement, and the part of the guide which clears the applied tufts out of the way of the tuft applying devices, instead of moving backwardly over an applied tuft, turns forwardly and at the end of a complete revolution is in position to press the applied tufts out of the way of the descending tuft-applying devices. This tuft guide is intermittently rotated through the medium of gears and shafts, and the use of reciprocating parts for operating the tuft guide is avoided, which is desirable in ma-

chines of this character which operate at 50 relatively high speeds.

In the accompanying drawing,

Fig. 1 is a front elevation of a part of an automatic brush making machine equipped with my improvements;

Fig. 2 is a section approximately on the line 2—2 of Fig. 1, showing the tuft applying devices raised and the tuft guide approaching its position of rest;

Fig. 3 is a similar view showing the tuft applying devices in their lower positions, and the tuft guide in its position of rest;

Fig. 4 is a front elevation of the tuft guide; and,

Fig. 5 is a top plan view of the same.

Referring to the drawing, *a* represents the frame of the machine on which is mounted a main shaft 1 and a counter-shaft 2, which is driven from the main shaft by means of a chain belt 3. Upon the main shaft is a 70 crank arm 4, shown in dotted lines in Fig. 2, and a link 5 connects this arm with a rocking lever 6, pivoted at its center on a stud 7, which is secured to the frame *a*, and the opposite end of the rocker is connected 75 to a link 8, which, in turn, is connected to vertically movable tuft-applying devices comprising a pair of staple guides 9, and a staple driver 10 which is movable with said guides. When the machine is in motion, the tuft applying devices are reciprocated between the positions shown in Figs. 2 and 3. In moving downward, these devices co-operate with wisp gathering and staple forming mechanism to apply a staple 80 to the wisp and carry these downward and drive the staple into the brush block, indicated at 11. The brush block is mounted upon a table 12 which is automatically shifted after each tuft has been applied to 85 position the block for receiving the next tuft. As the staple forming and table shifting mechanisms are not a part of the present invention they are not shown or described.

Above the table is shown the tuft guide *b* of my invention. This guide, as shown in the drawing, comprises parallel guide plates

13, which are spaced apart by a wall or bridge piece 14, the latter connecting the lower forward edges only of the plates, the upper forward edges 13^a being separated, as shown in Fig. 4, and the top, rear and bottom edges or margins of the plates being also entirely separated. The general contour of the tuft guide is somewhat oblong with internally grooved portions 13^b running from top to bottom. The bridge piece 14 inclines upwardly and forwardly from the lower ends of the plates, and its outer face 14^a is channeled or grooved longitudinally, as shown, to effectively engage the applied tufts. A boss 13^c projects at right angles to the outer face of one of the plates, at or near its central portion, and this boss fits on to one end of a horizontal shaft 15 which is mounted in suitable bearings on the frame 20 of the machine. The tuft guide is positioned so that the lower tapering ends 9^a of the staple guides 9 will pass into the tuft guide when the latter is in the position shown in Fig. 3, and as the staple guides move downward with the staple and tuft, the ends of the latter will be guided by the grooves 13 and the staple will be forced into the block, to secure the tuft, by the driving rod 10. As the staple guides move upward, the tuft guide turns in the direction of the arrow, Figs. 2 and 3, and in so doing the bridge piece 14 passes forwardly through the tufts which have previously been driven into the block, and at the end of its revolution the bridge piece is at the rear of the tufts, as shown in Fig. 2. Thus, the bridge piece, instead of moving backwardly over the tuft to clear it, moves forwardly and returns at the rear of the tuft, and moves the bristles 40 out of the path of the tuft-applying devices.

The shaft 15 which carries the tuft guide is connected by bevel pinions 16 to an upwardly inclined shaft 17, which carries a bevel pinion 18. This latter pinion engages 45 a mutilated bevel pinion 19, upon the shaft 2 which is driven from the main shaft 1. The gear or pinion 19 is provided with teeth extending approximately half way around its circumference, and when the staple guides 9 are in their uppermost position and about to descend, which position is shown in Fig. 2, the tuft guide is in the position shown in said latter figure, the bridge piece 14 being at the rear of the tufts and the tuft guide itself approaching its position of rest. As the staple guides 9 descend, the tuft guide reaches the vertical position,—that is, the position in which its grooves 13^b are vertical,—and it then comes to rest by 50 reason of the teeth on the mutilated gear passing out of engagement with the teeth on the gear 18. The tuft applying devices pass into the guide and deliver the tuft while the guide is stationary, and as the tuft applying devices start to ascend, the teeth on the mu-

tilated gear engage the teeth on the gear 18 and the tuft guide is rotated in the direction of the arrow, from the position shown in Fig. 3, to that shown in Fig. 2, while the tuft applying devices are moving upward. 70 As the said devices start to descend, the tuft guide moves again to the position shown in Fig. 3, where it dwells until the next tuft is delivered, and then makes another revolution, and so on as long as the machine is in 75 motion. The tuft guide starts to move from its position of rest, shown in Fig. 3, immediately after the staple guides have started to move upwardly, and as the upper parts of the plates forming the tuft guide are not 80 connected, the tuft guide can turn while the staple guides are completing their upward movement.

What I claim is:

1. In a brush-making machine, the combination with reciprocating tuft-delivering devices, of a tuft guide adapted to receive said devices and comprising two parallel guide plates connected at their lower forward edges by a bridge-piece, said plates 85 extending above the bridge-piece, the rear edges of said plates and their forward edges above said bridge-piece being unconnected, and means for intermittently rotating said guide in time with the movements of said 90 devices.

2. In a brush-making machine, the combination with reciprocating tuft-delivering devices, of a tuft guide adapted to receive said devices and comprising two parallel 100 guide plates and a bridge-piece connecting the lower forward edges of said plates, a shaft secured endwise to the central part of one of said plates, said plates extending above the shaft and the rear edges of said 105 plates and their forward edges above the shaft being unconnected, and means for intermittently rotating said guide in time with the movements of said devices.

3. In a brush-making machine, tuft guiding mechanism comprising a shaft and a tuft guide secured to one end of said shaft, said guide comprising two parallel spaced guide plates lying in planes at right angles to the axis of the shaft and a bridge-piece 110 connecting their lower forward edges only, said bridge-piece having a concave outer face.

4. In a brush-making machine, the combination with reciprocating tuft-delivering devices, of a tuft guide adapted to receive said devices and comprising parallel guide plates and a bridge-piece connecting the lower forward edges of said plates only, and means for intermittently rotating said guide 115 in time with the movements of said devices.

5. In a brush-making machine, the combination with reciprocating tuft-delivering devices, of a tuft guide adapted to receive said devices and comprising parallel guide 120

plates and a bridge-piece connecting the lower forward edges of said plates only, a shaft having one end secured to the side of one of said guide plates, and gearing adapted to give a partial rotation to said shaft and guide while the tuft delivering devices are approaching the guide, to allow said

shaft and guide to stop while said devices are in the guide, and to complete the rotation of the shaft and guide while said devices are retreating from the guide. ¹⁰

In testimony whereof I hereunto affix my signature.

CHARLES E. FISHER.
